I. BENJAMINS

HOISTING MECHANISM

Filed Nov. 6, 1920

FIG. 6.

FIG. 9.

FIG. 8.

Inventor
Israel Benjamins.

UNITED STATES PATENT OFFICE.

ISRAEL BENJAMINS, OF BROOKLYN, NEW YORK.

HOISTING MECHANISM.

Application filed November 6, 1920. Serial No. 422,368.

To all whom it may concern:

Be it known that I, ISRAEL BENJAMINS, a citizen of the United States, residing at Brooklyn, in the county of Kings and State 5 of New York, have invented a new and useful Hoisting Mechanism, of which the following is a specification.

My invention relates to improvements in hoisting mechanisms which may be used 10 for dental and barbers' chairs, as jacks for automobiles, carriages and wagons, also for scaffolds and for sundry other purposes for which the construction of my hoisting mechanism is adapted, and it consists in the novel 15 features hereinafter more fully described.

The objects of my improvement are:

First, to provide a collapsible hoisting mechanism with a base pivotally connected to the lower ends of the legs thereof, with- 20 out having any sliding parts at said base.

Second, to provide a saddle of constant length for the support of the load, said saddle being also pivotally connected to the upper ends of the bars or links composing 25 my hoisting mechanism, also without any sliding parts at said saddle.

Third, to distribute the load on both 30 panels of my hoisting mechanism substantially equally, thereby reducing the strains thereon.

Fourth, to have my hoisting mechanism, when employed as a jack for automobiles, operated by a key wrench extending rear- 35 wardly of the automobile into a convenient position for the operator; and

Fifth, to have my hoisting mechanism simple, durable, light and inexpensive.

I attain these objects by the mechanism illustrated in the accompanying drawings or 40 by any mechanical equivalent or obvious modification of the same.

In the drawings Fig. 1 is a side elevation of my hoisting mechanism, with the ends of the screw 22-23 broken off; Fig. 2 is a section on the line C-D of Fig. 1, with the 45 screw omitted.

Fig. 3 is an elevation of one of the bearing pins 29-27, looking from right to left in Fig. 1.

Fig. 4 is a plan of the saddle 30-31; Fig. 5 is a section of the saddle on the line A-B of Fig. 1.

Fig. 6 is an elevation of one end of the screw 22-23 showing the tapered connection to the key wrench 25;

Fig. 7 is an end view looking from right

to left in Fig. 6; Fig. 8 is a cross-section of the socket end of the key wrench; Fig. 9 is an elevation of the key wrench partly broken off and showing the handle as broken off at both ends.

Similar numerals and letters refer to similar parts throughout the several views. 11 and 12 are a pair of inclined links or bars, pivotally connected at their lower ends to 65 the base 20 by means of the pins 33 and 32 respectively, and shown as crossing each other at a variable point of their length; the upper ends of said bars 11 and 12 are pivotally connected each to one end of the 70 nuts 19 and 18 respectively by means of the pins 34 and 35 respectively.

11^a and 12^a are a pair of bars pivotally connected at their lower ends to the base 20 by means of the pins 32 and 33 respectively; 75 the bar 11^a is parallel to the bar 11, and the bar 12^a is parallel to the bar 12; the upper ends of the bars 11^a and 12^a are pivotally connected to the nuts or position members 19 and 18 respectively by means of the pins 80 34^a and 35^a respectively. The distance between the centers of the pins 34 and 34^a is the same as the distance between the centers of the pins 33 and 32, which is also the distance between the centers of the pins 35 85 and 35^a.

It is, therefore, evident that the nuts 18 and 19 will always remain parallel to the base 20 for all angles of inclination of the bars 11 and 12, which are always equally inclined to the base 20.

13 and 14 are a pair of bars similar to the bars 11 and 12 and pivotally connected at their lower ends to the nuts 19 and 18 respectively by means of the pins 36 and 37; 13^a and 14^a are a pair of bars parallel to the bars 13 and 14 and pivotally connected at their lower ends to the nuts 19 and 18 respectively by means of the pins 36^a and 37^a.

The bars 13^a and 14, also 13 and 14^a, are pivotally connected at their upper ends by means of the bearing pins 29-27, which have each therein a cylindrical opening 28 adapted to receive one end 31 of the saddle 30.

The distance between the centers of the pins 29 is the same as the distances between the centers of the pins 37 and 37^a and the centers of the pins 36^a and 36.

The saddle 30 is, therefore, substantially parallel to the nuts 19 and 18 for all posi-

tions of the bars 13 and 14, which are equally inclined to said saddle 30, except that the saddle 30 has a slight depression, as shown in Fig. 1, to fit the load, which may be the axle of an automobile.

Two panels of bars 13, 14, 13^a and 14^a may be used, the same as of the bars, 11, 12, 11^a and 12^a, as shown in Fig. 2.

The journals 31 are provided in the saddle 30, as well as the bearings 28 in the pins 29—27, to permit the load to adjust itself to any angle, as when the axle of an automobile is inclined, and to strain both panels of the hoisting mechanism equally or nearly so.

22 and 23 is a right and left screw adapted to move the nuts 18 and 19 towards each other to raise the load or away from each other to lower the load; one or both ends of the screw 22—23 may be tapered and squared as shown at 24 in Figs. 6 and 7 and adapted to fit a key wrench 25, which is provided at one end with a socket to fit the end 24 of the screw 22—23, and the other end with 25 a vise-handle 26.

The key wrench 25 may be made long enough to place the handle 26 beyond the body of an automobile and beyond all other obstructions, thereby rendering the hoisting mechanism more accessible and easy to operate.

Many other changes could be made in the details of my hoisting mechanism without departing from the main scope of my invention.

I do not therefore restrict myself to the details as shown in the drawings; but I intend to include also all mechanical equivalents and reasonably obvious modifications 40 of the same within the scope of my invention.

What I claim as my invention, and desire to secure by Letters Patent is:

1. In a hoisting mechanism a base, a pair of inclined bars, pivotally connected thereto at their lower ends, a pair of position members, pivotally connected to the upper ends of said bars, and a means for moving said members towards or away from each other, 45 combined with a pair of bars parallel to said inclined bars and pivotally connected at their lower ends to said base, and at their upper ends to said position members, thereby insuring the stability of the mechanism.

2. An apparatus of the character described comprising a base, a movable support, a plurality of pairs of link members pivotally secured together and to said support and said base, engageable members secured to the outer intermediate ends of said link members, engageable members secured to the inner intermediate ends of said link members and a revoluble member for actuating said engageable members whereby to 60 operate said link members and raise or

lower said movable support, substantially as specified.

3. In a hoisting mechanism a base, a pair of inclined bars, pivotally connected thereto at their lower ends, a pair of position members, pivotally connected to the upper ends of said bars, and a means for moving said members towards or away from each other, combined with a bar parallel to one of said inclined bars and pivotally connected at its lower end to said base and at its upper end to one of said position members, thereby insuring the stability of the mechanism.

4. An apparatus of the character described comprising a base, a movable support, a plurality of connecting members, each comprising four links having their ends pivotally connected together and two of said connected ends secured to said movable support and two of said connected ends secured to said base, engageable members secured to the connected intermediate outer ends of each pair of said links, engageable members secured to the intermediate inner ends of each of said pair of links and a revoluble member traversing said engageable members, whereby to actuate the same to raise or lower said movable support, substantially as specified.

5. In a hoisting mechanism a pair of position members, a means for drawing said members towards or away from each other and two opposite sets of inclined bars, pivotally connected at their lower ends to said members and at their upper ends to the opposite ends of a pair of pins, combined with bearings in said pins and a saddle for the load having at its ends journals swivelled in said bearings, thereby distributing the load on both sets of bars substantially equally and thereby reducing the strain thereon.

6. An apparatus of the character described comprising a base, a movable support, a plurality of connecting members each formed of four links having their ends pivotally connected together and forming overlapping parallelograms, said connecting members having their upper and lower ends respectively secured to said movable support and to said base, nuts pivotally secured to the connected intermediate ends of said connecting members, and a screw traversing said nuts for actuating the same and their related parts whereby to raise or lower said movable support, substantially as specified.

7. An apparatus of the character described comprising a base, a pair of outwardly projecting studs upon the opposite sides thereof, a movable support, outwardly projecting studs upon its opposite sides, a plurality of connecting members each formed of four links having their ends

pivotedly connected together and forming overlapping parallelograms and secured to the studs upon the opposite sides of said movable support and said base, nuts pivotally secured to the connected intermediate ends of said connecting members, and a screw in threaded engagement with said nuts for actuating the same and their related parts, whereby to raise or lower said movable support and to hold the same locked ¹⁰ to any intermediate position, substantially as specified.

ISRAEL BENJAMINS.
